UNITED STATES PATENT OFFICE.

WALTER F. BANKS, OF MILFORD, CONNECTICUT, ASSIGNOR TO THE NATIONAL ELECTRICAL MANUFACTURING COMPANY, OF SAME PLACE.

SWITCHBOARD APPARATUS.

SPECIFICATION forming part of Letters Patent No. 588,258, dated August 17, 1897.

Application filed October 1, 1896. Serial No. 607,549. (No model.)

To all whom it may concern:

Be it known that I, WALTER FREDERICK BANKS, a resident of Milford, New Haven county, State of Connecticut, have invented 5 certain new and useful Improvements in Switchboard Apparatus, of which the following is a specification.

My invention relates to switchboard apparatus, more especially applicable to district 10 telephone-circuits.

To this end my invention consists in the special matters hereinafter pointed out and claimed.

My invention will be understood by referring 15 to the accompanying drawings, in which—

Figure 1 is a front elevation of a switchboard apparatus embodying my invention. Fig. 2 is a rear elevation thereof. Fig. 3 is a 20 section thereof on line 3 of Fig. 2. Fig. 4 is a detail view of the lower row of plugs shown in Fig. 3, the direction of view being upward. Fig. 5 is a detail diagram of the switchboard-circuits, and Fig. 6 is another arrangement 25 of circuits.

In the drawings, A is a switchboard, which is provided with a series of line-drops D' D² D³ D⁴ D⁵ D⁶ D⁷ and a ringing-off drop R D. The board is also provided with an upper row 30 or series of plugs or buttons B' B² B³ B⁴ B⁵ B⁶ B⁷, which in the present instance constitute the office-telephone-set plugs, and also with a series of plugs C' C² C³ C⁴ C⁵ C⁶ C⁷, which in the present instance constitute the cross-connecting plugs. 35

Before proceeding to describe my switchboard in detail I will state that the operation is as follows: A series of lines come into the switchboard, each of which lines terminates 40 in a line-drop. When a call comes in, the line-drop falls, exhibiting its number. Thereupon the appropriate office-telephone-set plug in the upper row is pulled out, which cuts out the line-drop and cuts in the central-office telephone set. In case the caller 45 desires merely to converse with central no further manipulation is necessary. If, however, one caller desires to communicate with another, say "3" has called and wishes to talk to "5," the operator at the desk first 50 calls "5" and, getting a response from him,

pulls out C³ and C⁵ in the lower row and cuts his own instrument out of the line by pushing in the plugs B³ and B⁵ of the upper row, which he pulled out to enable him to 55 connect with "3" and "5," leaving "3" and "5" to converse, a ring-off drop being placed across the circuit by the act of joining the lines of "3" and "5."

Referring now particularly to Figs. 2, 3, and 60 4, it will be observed that below the annunciator-drops the board carries a pair of metallic strips E E'. To the metallic strip E a series of contact springs or plates e are electrically connected and to the metallic strip E' 65 a similar series of contact springs or plates e' are electrically connected.

In proximity to the springs or plates e' is a series of contact springs or plates d, which are insulated from and somewhat longer than the 70 springs or plates e e'. Connected to the buttons B' to B⁷ are push-rods F, which pass through guiding-braces G and are provided with insulated blocks H, which carry metallic contact-plates h h'. The contact-plates h co- 75 operate with the contact-springs e, and the contact-plates h' co-operate with the contact-springs e' and d. Connected to the contact-springs d are the terminals of the annunciator or line drops D' to D⁷, inclusive, and bridging 80 across from the metallic strip E to the metallic strip E' is the station telephone set S, which is clearly indicated in Fig. 3. Below the metallic strips E E' are metallic strips J J'. Springs j are in electrical connection with the 85 metallic strip J, and springs j' are in electrical connection with the metallic strip J'. A second and longer series of springs b is provided, which springs correspond in function with the springs d. Plugs similar to the plugs H are 90 employed in connection with this lower set of springs.

In Fig. 5, R D is the ringing-off drop, and D' is the calling or line drop of the first line. In this figure the current enters at E², a subscriber's line-terminal, and passes by the wire 1 to the contact-piece h'. Thence it passes to the spring d, through the calling-annunciator drop D' to the spring b, and thence out by the contact-piece h², which corresponds on the 95 lower set of plugs to the contact-piece h on the upper set of plugs, being the upper con- 100

tact-piece thereof, (the lower contact-piece being represented by h^4 .) and thence by wire 2 to the terminal E^4 . As the calling-current, say from subscriber No. 1, passes over the 5 circuit just named the drop D' falls, and thereupon the operator pulls out the plug B' , thereby bringing the plate h into contact with the spring e and the plate h' into contact with the spring e' , drawing the said contact h' away 10 from the spring d . By this means the office telephone set is cut into the subscriber's line and the drop D' is cut out of circuit. If the party calling wishes to communicate with another, say with B^3 , the operator pulls out the 15 plug C' and the plug C^3 , and it being remembered that the act of pulling out any two line-plugs in the lower row on the board brings these two lines into electrical connection with the metallic strips $J J'$ it will be obvious that 20 under this condition the two lines are in series with each other and that since the ringing-off drop $R D$ is bridged across from J to J' provision is made for indicating a ringing-off signal at the completion of the conversation. 25 Having described the modification shown in Fig. 5, I will now proceed to describe the form of arrangement of circuits shown in Fig. 6.

Referring particularly to Figs. 3, 4, and 6, it will be observed that the switchboard is 30 provided with a set of contact springs or plates k , which are connected to each other by the wire 3, and is also provided with a set of contact-springs l , which are mounted on the rail G , but are insulated therefrom. The 35 plugs are also provided with contact-points m and m' and are adapted to contact with a spring k or l , the contact being made by the plug m' with a spring k when the plug is out and by the contact m with the spring l when the plug is 40 in—that is to say, in its normal position. These two positions are clearly illustrated in Figs. 3 and 4. The contact-points m' are connected together—that is to say, the contact-point m' of the plug b' is connected to the 45 contact-point m of the plug c' , and so on throughout the board. The contact-points m are also connected together in the same manner—that is to say, the contact-point m of the plug b' is connected to the contact-point m of the 50 plug c' , and so on with said line throughout the board.

In Fig. 6 I have shown the contacts m' as connected by wire 4 and the contacts m as connected by wire 5.

55 The arrangement shown in Fig. 6 is especially adapted for use in situations where a signaling-line having a battery is used as a common return for the telephone-line when the telephone is in use to transmit speech as 60 distinguished from mere calling, the battery serving also as a calling-battery to throw the drop on the switchboard. So, therefore, in Fig. 6 I have shown a telephone-line T as running to a terminal E^4 and a signaling-line U having a battery B' therein and a connection 65 8 running from the said line ahead of the said battery to the terminal E^5 and a connection 9

running from the said line behind the battery to the terminal E^2 , the terminal E^2 being connected to the contact l of the upper row of plugs by a wire 6 and the terminal E^5 being connected to the contact-points m' by wire 7. By this means the battery can be employed to throw the drop to call central, and will then be cut out by the movement of the plug, so 75 that the battery will not be in a telephone-line when the circuit is finally completed for talking. This is accomplished as follows: Supposing the parts to be in the positions shown in Fig. 6 and a call comes to the central, it 80 passes from the telephone-line T by terminal E^4 , wire 2, contact-plate h^3 , contact-spring b , calling-drop D' , contact-spring d , contact-plate h' to contact-plate h^4 by wire 10 to the point 11, up to which point the arrangement 85 is identical with the arrangement shown in Fig. 5. Thence the current passes while the apparatus is in its present or normal condition by the spring l , contact-point m , wire 5 to the other spring l and wire 6 to the terminal 90 E^2 , thence by wire 9 and battery B' to the signal-line U , forming a metallic circuit, including the battery. The operator now pulls out the plug in the upper row which corresponds to the drop which has been thrown and thereupon cuts his telephone set into the line of the caller by bringing the contact-plates h' and h into contact with the springs e' and e , respectively, of his telephone set in the same manner as was done in the apparatus shown 95 in Fig. 5 and at the same time breaking the contact between m and l and bringing m' and k together. The condition of things is now 100 changed and a new path from point 11 is established by wire 3, spring k , contact-point m' , wire 7, terminal E^5 , and wire 8 to the signal-line ahead of the battery, so that the battery will not be in circuit to interfere with telephonic operations. If now the caller desires to communicate with another party on 105 another line, he makes known his desire, and thereupon the operator at the central pulls out the two plugs in the lower row corresponding to the two lines to be connected and pushes in the plug formerly drawn out. This 110 puts the two parties in communication with each other and leaves out the battery, the manipulations being the same as in the case 115 just described.

Having described my invention, what I 120 claim, and desire to secure by Letters Patent, is—

1. In a telephone system, the combination of a plurality of contact-strips, a plurality of contact-springs $e e'$ connected thereto, a series of contact-strips d of greater length than the contact-springs $e e'$ and insulated from each other and from the contact-strips $e e'$, a plug, contact-plates $h h'$ mounted thereon, contact-springs $k l$ and contact-pieces $m m'$ 125 coöperating with $k l$.

2. In a telephone system, the combination of a plurality of subscribers' lines each connected to a plurality of pairs of switchboard

contact-pieces, the said pairs being arranged in sets, calling-annunciators connected across each subscriber's contacts from a contact on one pair to a contact on the other pair, a central-office telephone set adapted for coöperation with one of the pairs, and a universal connection such as the contact-strips J and J' with their contact-springs to which the second pair of contact-points of each subscriber's line is adapted to be connected, substantially as described and for the purposes set forth:

3. In a switchboard apparatus, the combination of a telephone-line and a signal-line having a battery, the said signal-line when the telephone-line is in use, forming a common return for the telephone-line so that the signal-line and telephone-line constitute a metallic circuit, a central station having a contact for each telephone-line, a plurality of outgoing terminals at central, one terminal being connected ahead of the battery at the central station and the other terminal being connected behind the battery at the central station and contact devices in circuit with the said plurality of outgoing terminals, and a switching device at the central station for switching the connection of the telephone-line from one side of the battery to the other.

4. In a telephone-switchboard apparatus, the combination of a telephone-line running to a central station and a signaling-line also running to the central station and having a battery at central, the said signaling-line forming a common return for the telephone-line, a contact for each telephone-line at the central, a plurality of outgoing terminals at the central, one terminal being connected to

the signaling-line ahead of the battery and the other terminal being connected to the 40 signaling-line behind the battery and contact devices at the central station adapted to coöperate with the said outgoing terminals, a switching device at the said central station for switching the telephone-contact into connection with the signaling-line ahead of the battery or behind the battery by connecting the said contact with one or the other of the outgoing terminals.

5. In a switchboard apparatus, the combination of a telephone-line and a calling-line having a battery and forming a common return for the telephone-line when the said telephone-line is in use for transmitting speech as distinguished from calling, so that the calling-line and the telephone-line are included in the same talking-circuit, a plurality of outgoing terminals at the central, one terminal being connected to the calling-line at the central station ahead of the battery in the said 55 calling-line and the other terminal being connected to the calling-line at the central station behind the battery in the said calling-line and a switching device or plug for connecting the telephone-line with one or the other of the outgoing terminals, whereby a call may be received at the central station over the telephone and calling line and by manipulating the plug or switch the telephone-line may be thereupon connected to 60 the calling-line so as to cut the battery out of the telephone talking-circuit.

WALTER F. BANKS.
